CLAIM

The ornamental design for a pharmaceutical product cassette for an injection device, as shown and described.

DESCRIPTION

FIG. 1 is a top perspective view of a pharmaceutical product cassette for an injection device showing the new design; FIG. 2 is a bottom perspective view thereof;

FIG. 3 is a bottom elevation view thereof;

FIG. 4 is a top elevation view thereof;

FIG. 5 is a side elevation view thereof;

FIG. 6 is a front view thereof; and,

FIG. 7 is a rear view thereof.

The broken lines represent the portions of the design that form no part of the claim.
